CLAIM

The ornamental design for a dispenser for sheet material held in rolls, as shown and described.

DESCRIPTION

FIG. 1 is a front, right side and top perspective view of a dispenser for sheet material held in rolls showing our new design;

FIG. 2 is a front elevational view thereof;

FIG. 3 is a top plan view thereof; and,

FIG. 4 is a bottom plan view thereof.

The claimed design resides in the dispensing mouth portion of the dispenser which is shown in unbroken lines and provide with surface shading. The broken-line disclosure immediately adjacent to the claimed design is intended to represent an unclaimed boundary between claimed and unclaimed subject matter, and the remaining broken-line disclosure is understood to represent portions of the article in which the claimed design is embodied, but which forms no part of the claimed design.
